United States Patent Office.

JOHN R. LOMAS, OF NEW HAVEN, CONNECTICUT, ASSIGNOR TO THE
"B. SHONINGER MELODEON COMPANY," OF SAME PLACE.

Design No. 2,807, dated October 22, 1867.

DESIGN FOR AN ORGAN-CASE.

The Schedule referred to in these Letters Patent and making part of the same.

TO ALL WHOM IT MAY CONCERN :

Be it known that I, JOHN R. LOMAS, of the city and county of New Haven, in the State of Connecticut, have invented a new and useful improvement in Design for Organ-Case, to be called the Eureka Case; and I do hereby declare that the following is a full, clear, and exact description of the construction, character, and operation of the same, reference being had to the accompanying drawings, which make part of this specification, in which—

Figure 1 is a perspective view of the front of the case, showing the general appearance.

Figure 2 is a section, cut horizontally through, showing the recess for the feet, &c.

What I claim as my invention, and desire to secure by Letters Patent, is—

The design or configuration herein described and set forth, and fully shown in the drawing.
